**MOTOR PUMP HOUSING FOR A DENTAL
JET CLEANSING UNIT AND COVER
THEREFOR**

Frederick Gordon Mackay, Tarzana, Calif., John W. Mattingly, Fort Collins, Colo., and Allan B. Johnson, Tarzana, Calif., assignors to Aqua Tec Corporation, Denver, Colo., a corporation of California

Filed July 10, 1967, Ser. No. 7,750

Term of patent 14 years

(Cl. D24—1)

FIG.1

FIG.2

FIG.3

FIG.4

FIG.5

FIG.6

FIG. 1 is a perspective view of a motor pump housing for a dental jet cleansing unit and cover therefor embodying our new design;

FIG. 2 is a front elevation thereof;

FIG. 3 is a left side elevation thereof;

FIG. 4 is a right side elevation thereof;

FIG. 5 is a rear elevation thereof; and

FIG. 6 is a top plan view thereof.

The dominant features of our design reside in those portions shown in full lines in the drawings.

The broken line representation of the electric cord is fragmentarily shown for illustrative purposes only.

We claim:

The ornamental design for a motor pump housing for a dental jet cleansing unit and cover therefor, as shown and described.
